CLAIM

The ornamental design for a golf caddy, as shown and described.

DESCRIPTION

FIG. 1 is a front left side perspective view showing the new design for a golf caddy;

FIG. 2 is a rear right side perspective view thereof;

FIG. 3 is a front elevation view thereof;

FIG. 4 is a rear elevation view thereof;

FIG. 5 is a right-side view thereof;

FIG. 6 is a left-side view thereof;

FIG. 7 is a top plan view thereof;

FIG. 8 is a bottom plan view thereof;

FIG. 9 is a front left side perspective view showing the golf caddy with accessories exploded away therefrom;

FIG. 10 is a front left side perspective view showing the new design for a golf caddy;

FIG. 11 is a rear right side perspective view thereof;

FIG. 12 is a front elevation view thereof;

FIG. 13 is a rear elevation view thereof;

FIG. 14 is a right-side view thereof;

FIG. 15 is a left-side view thereof;

FIG. 16 is a top plan view thereof; and,

FIG. 17 is a bottom plan view thereof.

The broken-dash-dot lines illustrate stitching and form no part of the claimed design. All other broken lines show portions that form no part of the claimed design.
